UNITED STATES PATENT OFFICE.

ERNEST J. NOEL, OF READING, PENNSYLVANIA.

BUNCH BUILDER.

Application filed May 9, 1925. Serial No. 29,220.

This invention relates to bunch building mechanisms for the builder motions of spinning frames, and particularly to a bunch builder motion which acts upon the builder arm to prevent the cam normally operating on the builder arm from shifting the builder arm to its full extent, or in other words a bunch builder mechanism which immediately after doffing permits only the apices of the cam points to operate upon the builder arm so that only a short oscillatory motion is given to the builder arm and which, after the bunch is completed, automatically permits the cam to operate upon the builder arm to secure the full reciprocation of the builder arm and thus the full reciprocation of the ring rail under the builder motion.

A further object is to provide a mechanism of this character which is relatively simple, compact, and which is so constructed that it is a relatively easy matter to provide for any desired number of winds of the filling upon the bobbin in order to form the bunch so that only a few winds of the filling may be placed upon the bobbin as desired or as many as desired.

A still further object is to provide a motion of this character which will provide a bunch wherein the yarn is not disposed upon the bobbin by any up and down movement of the ring rail at all but is wound upon the bobbin without any traverse.

Another object is to provide a mechanism of this character wherein the limitation of the movement of the builder arm is secured by a member operatively mounted upon the builder arm and shifted into action when the frame is doffed, which is provided with gear teeth engaging a pinion on the cam shaft, and which will operate a length of time dependent upon the number of gear teeth on the member, this member being approximately sector-shaped and when it escapes from the gear wheel or pinion dropping down into its inoperative position immediately, thus permitting the regular traverse of the ring rail to be resumed.

Other objects will appear in the course of the following description.

My invention is illustrated in the accompanying drawings, wherein:—

Figure 1 is a fragmentary front elevation of a spinning frame having my improved bunch building mechanism applied thereto; Figure 2 is a section on the line 2—2 of Figure 1;

Figure 3 is an enlarged elevation showing my bunch building mechanism applied;

Figure 4 is an edge elevation of the bar 10 showing the means for supporting the bunch building gear wheel in connection with the cam;

Figure 5 is a side elevation of the structure shown in Figure 3, showing the position of the parts when the builder arm moves upward.

Figure 6 is an elevation of the bunch building segment gear;

Figure 7 is a perspective view of the cover therefor;

Figure 8 is a sectional view on the line 8—8 of Figure 6;

Figure 9 is a side elevation of another form of bunch building segment gear.

Referring to these drawings, it will be seen that I have illustrated sufficient of a spinning mechanism to illustrate the application of my invention, and referring to these drawings A designates part of the frame of the spinning mechanism, B the spindle rail, C the ring rail, and D the spindle or bobbin. The rail C is mounted upon vertically shiftable rods E operated by the usual rockers F, these rockers being connected to each other in the usual manner and each of these rockers having the form of a T-shaped lever, one arm of which is weighted, as at f, the other arm extending beneath the foot of the vertically reciprocable ring rail carrying rod E.

Connected to the upper end of the rocker F is the chain G which extends over the pulley g and which extends down to the builder arm H, this builder arm being of an ordinary construction and provided with the usual drum I operated by means of the worm i carried upon the pick shaft J, which in turn carries the pick wheel j which is operated by the usual pawl or like member so that as the arm H moves upward the pick wheel j will be engaged by the pawl and given a certain predetermined revolution which will cause the unwinding of the drum I to permit the chain G to slack up and thereby permit the ring rail to move higher. The arm H is operated by means of the main cam K which is illustrated as a four-lobed cam but may be of any suitable form, this cam operating upon a roller carried by the arm H. So far I have described the ordinary and common builder motion found on spinning machines.

In order to carry out the purposes of my invention, I provide a supporting rod 10, the upper end of which is formed with a longitudinally extending slot 11 large enough 5 to receive and slide upon the shaft *h* of the cam K. Intermediate its ends this supporting rod 10 is formed with a longitudinally extending slot 12 and at its lower end it is formed to pivotally connect to a pin 13 10 which is operatively connected by a bracket 14 or like device to the arm H.

Mounted in the slot 11 is a pin 15, one part of which is screw-threaded, as at 16, to receive upon it the nut 17. The other half 15 of this pin 15 is cylindrical in form and a cotter pin 18 extends through the extremity of this end of the pin. Separating the screw-threaded portion 16 from the main part of the pin 15 is a collar 19. The screw-threaded 20 portion of the pin is adapted to be placed through the slot 11 and adjusted therein and held by the nut 17, and adapted to be slipped upon this screw-threaded portion 16 before it is placed in position is an annular member 20 having outwardly projecting clutch teeth. The clutch teeth are arranged and the member is so formed as to partially surround or enclose the collar 19, and adapted 25 to be disposed upon the cylindrical portion of the pin 15 is a wheel formed with interrupted gear teeth of a peculiar character, as will be later described, this wheel which is in the nature of a cam being designated 21. The inner face of this wheel is also provided 30 with clutch teeth 22 and is hollow so as to partially surround and enclose the collar 19, and when this gear 21 is placed upon the pin 15 the teeth 22 will engage with the teeth on the member 20 and the 35 gear wheel will be locked upon the pin 15 for rotation therearound. This wheel 21 is preferably somewhat sector-shaped and is cut away at a plurality of points to form approximately V-shaped valleys 24 between 40 outwardly projecting arms 25. As illustrated, there are five of these arms, though I do not wish to be limited to this number, and the extremity of each arm is formed with gear teeth 26. I have illustrated three gear 45 teeth upon the extremity of each arm, but here again I do not wish to be limited to this 50 number.

Connected to one of the end arms 25 is a two-part link consisting of the lower section 55 27 and the upper section 28. The upper section 28 has an aperture for the passage of the shaft *h* and swings loosely upon this shaft outward of the supporting rod. The lower end of this section 27 carries an outwardly projecting pin 29 and the section 27 is, therefore, pivotally connected to this section 28 by means of this pin 29. The section 27 is longitudinally slotted, as at 30, and a pin 31 on one of the arms 25 engages 60 65 in this slot and operatively connects this

arm to the sectional rod formed of the members 27 and 28.

It will be noted that the wheel 25 is in the nature of a cam and that the gear wheel 32 with which the member 25 operates constitutes an abutment against which this cam operates in order to alternately shift the arm H downward and permit the arm H to move upward. This cam is operated by the gear wheel 32 engaging with the teeth on the 70 extremity of the arms 25. The spaces between these arms constitute the reentrant portions of the cam while the protuberant portions of the cam are formed by the arms 25. 80

The operation of this invention so far as described is as follows: In the normal operation of the mechanism, while the regular layer of filling is being placed upon the bobbin or spindle, the arm H is relatively raised and the supporting rod 10 is lifted also, the slot 12 permitting this to be secured, as illustrated in Figure 3. Inasmuch as this rod 10 is raised, it follows that the rod formed of the members 27 and 28 will cause 90 the interrupted gear 25 to occupy the position shown in Figure 3. Under these circumstances it is inoperative and the builder motion is operated by means of the cam K in the usual manner with a full stroke given 95 to the ring rail over the builder arm. When the bobbins have been filled and the operator doffs the bobbins, the builder arm is lowered to its full extent. This shifts the supporting rod 10 downward relative to the shaft 100 *h*, and inasmuch as the upper end of the connecting rod formed by the members 27 and 28 is held from downward movement by engaging the shaft *h*, it follows that it will 105 act to rotate the cam wheel 25 into a position as illustrated in Figure 5, where the teeth 26 of the first arm of the series will engage with the teeth on the gear wheel 32. Then as the shaft *h* rotates, the member 25 will be 110 shifted toward the right in Figure 3 by the engagement of the teeth on the wheel 32 and the first finger or arm until the gear teeth 26 on the first finger or arm are just about to escape from the teeth on the gear wheel 32. At this time the teeth on the second finger 115 have engaged the teeth of gear wheel 32.

It will be noted that the spaces 24 on the member 25 are equal in number to the number of protuberances on the cam K. As a first arm of the member 25 moves from the position shown in Figure 3 to the position radial to the gear wheel 32 to the position shown for the second arm in Figure 5, the parts 25, 27 and 28 will permit a slight 120 upward movement of the rod 10 and of the arm H a slight degree as, for instance, three-eighths of an inch, which will cause a traverse of the ring rail C to this extent. As the second arm, however, comes from a position 125 to the left of the rod 10 into a position of 130

approximate alignment with this rod, it will again depress this arm H a slight amount and then as this second arm moves along under the operation of the gear 32, another 5 valley 24 will be brought opposite the rod 10 and there will be again a slight upward movement of the arm H until eventually all of the arms on the member 25 have been engaged by and disengaged from the gear 10 wheel 32 and then the bunch is formed. When this occurs, the weight of member 25 will cause it to shift to its normal and inoperative position, as illustrated in Figure 15 3, and thereafter the builder motion will operate in its normal and ordinary manner.

While I have illustrated a member 25 having five fingers or arms, I do not wish to be limited to this as it may have as many 20 lobes on the cam K and under some circumstances as, for instance, where it is not desired that any traverse shall be given to the bunch as the filling is wound upon the bobbin, I provide a cam member 25^a, illustrated in Figure 9, which is practically a sector of a circle and which is provided with gear teeth on its periphery adapted to engage the gear teeth 32. This member is also provided with clutch teeth 23^a whereby it 30 may be engaged with the member 20.

With this device, during the operation of portion 25^a the arm H is held down away from any action by the cam K at all and as a consequence the ring rail does not reciprocate at all and the yarn will be wrapped upon the bobbin in one plane or approximately in one plane. Obviously the extent 35 of the toothed surface of the sector gear 25^a and obviously the motion of the bunch builder or the size of the bunch built will also depend upon the angular distance between the end arms where the member 25 is provided with toothed arms, as illustrated. Thus, for instance, if there are two arms 40 on the member 25, it is obvious that filling for the bunch will be relatively small and if there are three arms it will be larger, and so on, and that by this means it is possible to very readily regulate the amount 45 of play which will form the bunch and if these arms are long relative to the arms shown in Figure 6, it is obvious that the valleys 24 will be deeper and, therefore, more traverse will be given in forming the bunch, whereas if the spaces 24 are shallower, less 50 traverse will be given in forming the bunch.

I do not wish to be limited to the exact construction or formation of the members 55 25 or 25^a, as this may be modified in many ways without departing from the spirit of the invention, but it will be seen that I have provided a device which is automatically placed in operation and which acts as long as it is in operation to give either no oscillation to the builder arm H, as where the

sector cam 25^a is used, or to give only a slight oscillation to the builder arm, as where the interrupted sector gear cam 25 is used and, as before remarked, it will be obvious that these members 25 may be 70 formed to have arms of various lengths, different numbers of teeth on the extremities of the arms, and may be readily adjusted to suit any circumstances of operation. The device is very compact and takes up but little room. This bunch builder can be used on any make of spinning machine and the length of space it occupies on the cam shaft is less than two inches.

Preferably a cover 33 will be used which 80 will partially enclose the cam wheel or the cam member 25^a. This cover, as illustrated, is formed with a web 34 having a slot 35 designed to accommodate the pin 15, this web 34 having a peripheral wall at the extremities of the arms 25 and then having a web 36 parallel to the web 34 but annular in form. This cover is made of metal and is designed to protect the gear 25 or 25^a from being moved by cleaners or sweepers. The 85 slot 35 is slipped back of the ratchet member 20 and the nut 17 is tightened up, thus holding the cover in place. The cover is very easy to remove but makes a good protection for the cam wheel.

I claim:—

1. In a builder motion the combination with a builder arm and primary means for giving oscillation thereto of normal amplitude, of a secondary cam carried by the builder arm and normally in an inoperative position, a member rotatable when said primary means is in operation and engaged by the secondary cam when the frame is doffed, said member acting as an abutment against 100 which the secondary cam bears during a part of its rotation and acting to rotate the secondary cam, and the secondary cam when in contact with the abutment member 105 acting to alternately depress the builder arm and permit it to lift, and means positively connecting the shaft of the primary cam to said secondary cam and acting to give a partial rotation to the secondary cam when the frame is doffed to bring the secondary cam 110 into engagement with said abutment.

2. In a builder motion the combination with a builder arm and a primary cam for giving oscillation thereto, of normal amplitude, of a segmental secondary cam carried 115 by the builder arm and normally in an inoperative position and having gear teeth, a gear wheel rotatable with said primary cam, means for rotating the secondary cam into engagement with the gear wheel when the frame is doffed to thereby cause a rotative movement of the secondary cam, said means positively connecting the secondary cam with the shaft of the primary cam, said gear 120 wheel acting as an abutment against which 125

the secondary cam bears during a part of its rotation, said secondary cam when in engagement with the gear wheel acting to alternately depress the builder arm and permit it to lift.

3. In a builder motion the combination with a builder arm and a primary cam for giving oscillation thereto of normal amplitude, of a secondary cam carried by the builder arm and normally in an inoperative position and having interrupted gear teeth upon its periphery, a gear wheel rotatable with the primary cam, means for swinging the secondary cam into engagement with said gear wheel when the frame is doffed to thereby cause the rotation of the secondary cam, said means including a connecting member between the secondary cam and the primary cam shaft, said member being non-extensible when the builder arm is moved away from the cam shaft but permitting the builder arm to move toward the cam shaft, said gear wheel acting as an abutment against which said secondary cam bears during a part of its rotation, said secondary cam when in engagement with said gear wheel acting to alternately depress the builder arm and permit it to lift, said secondary cam returning to its initial inoperative position when the teeth of the secondary cam have escaped from engagement with the teeth of the gear wheel.

4. The combination with a builder arm and primary means for giving oscillation thereto, of a bunch building cam having alternately reentrant and reentrant portions normally out of operative engagement with the builder arm but automatically shifted into operative engagement therewith when the frame is doffed and then acting to hold the builder arm out of operative relation to the primary oscillating means and giving said builder arm oscillation, and means actuated by the main driving means shifting the cam toward and into its normally inoperative position.

5. In a spinning frame, the combination with a builder arm and a primary cam for giving oscillation thereto of normal amplitude and a shaft coacting therewith, of a rod engaged at its lower end with the arm and at its other end slidably engaging said shaft, a gear wheel mounted on the shaft, a cam carried by the rod and normally out of operative engagement with the gear wheel, means operative when the frame is doffed acting to shift the cam into driving engagement with the gear wheel, the cam when so shifted shifting the rod and the arm connected thereto out of engagement with the primary cam, and means automatically releasing the cam from its engagement with the gear wheel after a predetermined period and returning the cam to its initial position.

6. The combination with a builder arm

and a primary cam giving oscillation thereto of normal amplitude, a shaft upon which the cam is mounted, of a rod engaged at its lower end with said arm and at its other end having sliding engagement with said shaft, a gear wheel mounted on the shaft, a cam carried by the rod and normally out of operative engagement with the gear wheel, a connecting rod engaged at its upper end with said shaft and at its lower end pivotally connected to the cam, means operative when the frame is doffed to shift the cam into driving engagement with the gear wheel, the cam fulcruming against said last named rod and thereby urging the first named rod downward to carry the arm out of the path of movement of the primary cam, said second named cam then operating to oscillate the arm, and means acting after a predetermined period to disengage the cam from the gear wheel and return the cam to its normally inoperative position.

7. In a spinning frame, the combination with a builder arm, a main cam for giving oscillation thereto, a shaft upon which the main cam is mounted, of a gear wheel mounted upon said shaft, a rod pivotally connected at its lower end to said arm and having sliding engagement with said shaft at its upper end, a sector-shaped cam mounted upon said rod and having gear teeth on its peripheral face engageable with said gear wheel in one position of the cam, and a connecting member engaged at its upper end with the shaft and at its lower end pivotally engaged with one corner of the cam and acting to shift the toothed portion of the cam into engagement with the gear wheel when the arm is lowered for doffing and the bar upon which the cam is mounted is correspondingly lowered.

8. In a spinning frame, the combination with a builder arm, a shaft, a primary cam mounted upon the shaft for giving oscillation to the builder arm, a gear wheel mounted upon the shaft and rotating therewith, a supporting rod pivotally connected at its lower end to the arm and slotted at its upper end to receive said shaft and move vertically thereon, a cam pivotally mounted upon said supporting rod and having alternate re-entrant and re-extrant portions, the re-extrant portions having gear teeth adapted to mesh with the gear teeth on the gear wheel, a connecting rod pivotally connected at its lower end to one corner of the cam and at its upper end having an aperture through which the shaft passes, said connecting rod acting, when the builder arm is lowered to doff the frame, to shift the cam into a position to carry its gear teeth into engagement with the gear wheel, the connecting rod being so formed as to permit the cam to rotate under the action of the gear wheel until its teeth have escaped engagement with the

teeth of the gear wheel and then to drop to an inoperative position.

9. In a spinning frame, the combination with a builder arm, a shaft, a primary cam mounted upon the shaft for giving oscillation to the builder arm, a gear wheel mounted upon the shaft and rotating therewith, a supporting rod pivotally connected at its lower end to the arm and slotted at its upper end to receive said shaft and move vertically thereon, a cam pivotally mounted upon said supporting rod and having alternate re-entrant and re-extrant portions, the re-extrant portions having gear teeth adapted to mesh with the gear teeth on the gear wheel, a connecting rod having its upper end swingingly engaged with said shaft, the lower portion of the connecting rod being slotted, a pin on the cam extending through the slot in the lower end of the connecting rod, said connecting rod acting, when the builder arm is lowered, to shift the cam into position to carry its teeth into engagement with the gear wheel for a predetermined period.
10. In a spinning machine, the combination with a builder arm, a primary cam for giving oscillations thereto of normal amplitude, a shaft upon which the cam is mounted, of a supporting rod pivotally engaged at its upper end with the builder arm and at its upper end having sliding engagement
- with the shaft, the middle of said arm being slotted, a pin passing through the slot and engaged with the arm, a sector-shaped cam pivotally mounted upon said pin, the cam having ratchet teeth upon its inside face, a ratchet clutch member mounted upon said pin and held from rotary movement and with which said ratchet clutch teeth are adapted to engage, a spring urging the cam toward the fixed clutch member, the cam having a toothed peripheral face adapted in one position of the cam to engage with the gear wheel, and a connecting rod swingingly engaged with the shaft and at its lower end longitudinally slotted, the cam having a pin engaging in said slot, said last named connecting rod, when the builder arm is lowered for doffing, acting to rotatably shift the cam to carry its teeth into engagement with the gear wheel to thereby cause the cam to shift downward on said rod upon which it is mounted and lower the builder arm out of operative relation to the primary cam, said connecting rod acting, when the builder arm is lowered, to shift the cam into position to carry its teeth into engagement with the gear wheel for a predetermined period.

In testimony whereof I hereunto affix my signature.

ERNEST J. NOEL.
